UNITED STATES PATENT OFFICE.

WALDO SHELDON, OF SOUTH NORWALK, CONNECTICUT.

WELL-DRILLING ENGINE.

Application filed April 19, 1927. Serial No. 184,846.

This invention relates to well drilling outfits and particularly those of the type disclosed in preceding applications, in which the motor is combined as a unit with the 5 rotary table, the table being mounted on one end of a sled-like frame and the motor being mounted on the opposite end of the same frame.

Special objects of the invention are to 10 provide a motor especially suited to this particular combination; which will have ample power for the purpose; which will have its weight distributed to the best advantage; be relatively free from vibration, 15 will be compact, fully accessible, well balanced on the frame and so arranged as to readily provide the desired speed ratios for driving the table, the hoisting drum, catheads and other drilling adjuncts.

20 These objects and others equally desirable are attained by a novel combination and arrangement of parts and special novel features, including in particular, the mounting of the engine cylinders directly over the 25 side beams of the frame at an angle to 90 degrees to each other, with the crank shaft journaled above and substantially over the longitudinal center of the frame and sprocket gearing of different gear ratios extending 30 from this overhead shaft down to a main drive shaft for the table and hoist journaled substantially on the longitudinal center of the frame.

Additional important novel features will 35 appear as the specification proceeds.

The drawings accompanying and forming part of this specification illustrate one practical commercial embodiment of the invention, but as this illustration is primarily for 40 purposes of disclosure, it will be understood that various structural modifications and changes may be made without departure from the true spirit and broad scope of the invention.

45 Figure 1 is a side elevation of the complete drilling unit with the engine embodied as a part of the same.

Figure 2 is an enlarged vertical cross sectional view taken on substantially the plane 50 of line 2-2 of Figure 1.

As best shown in Figure 1, the machine is built up on a sled-like frame having side sills and beams 5 in the nature of "runners" enabling the unit to be skidded into position on the cross beams 6 of the derrick floor.

Mounted on one end of the frame is the rotary table 7 supported on a base 8 secured on the side beams. This table is shown of the power feed type disclosed in other applications, having a drive sleeve 9 slidingly keyed in the table carrying clamping means 10 engaging the drill pipe 11 and adapted to be raised, lowered and held as required by pressure applying connections from the annular piston in the annular power cylinder 12.

The table is rotated by a bevel pinion 13 on the end of a drive shaft 14 journaled in bearings 15 on substantially the longitudinal center line of the frame. This shaft is shown as having a clutch 16 by which rotation of the table is controlled.

The engine for driving the table and hoist is mounted upon the opposite end of the frame and comprises a pair of cylinders 17 mounted over the side beams and arranged at substantially a 90 degree angle, said cylinders containing pistons 18 having rods 19, actuating crossheads from which connecting rods 20 extend to the crank 21 of the power shaft 22. This power shaft is journaled substantially on the longitudinal center line of the frame above and parallel to the drive shaft 14 and is connected with said drive shaft in the illustration by sprocket chains 23, 24 running from sprocket pinions 25, 26 down over sprocket gears 27, 28 on the drive shaft. The gears in these two drive sets are of different size so as to provide a two-speed drive from the power shaft down to the drive shaft and provision is made for selective use of either drive, in the present disclosure, by means of a sliding positive jaw clutch member 29 keyed on the drive shaft between gears 27, 28 and adapted to be coupled in engagement with either by the pivoted shifting lever 30.

The power shaft is shown as journaled in bearings 31 carried by the upright triangular frames 32, 33, 34 having their bases secured on the bed plate 35. This bed plate is bolted directly on the side beams and is shown as having a drop 36 in the center of the same carrying the two bearings 37 for this end section 14^a of the drive shaft. This end shaft section is shown as coupled with the main shaft section by a flexible coupling 38. This enables the engine to be readily uncoupled from the main section of the drive shaft and be removed as a complete entity. The bed plate and upright frames

constitute a rigid frame for holding the cylinders, power shaft and drive shaft section 14^a in proper relation when the engine is separated from the main frame.

5 The positioning of the engine cylinders directly over the side beams brings the main weight of the engine down to a low level and locates such weight in balanced relation at the sides of the frame. This construction 10 also lowers the overall height of the engine, the lightest parts are placed at the top, the engine shaft is located over the center of the frame and directly over the drive shaft and the two-speed sprocket gearing is made fully 15 accessible for repairs or for change of gear ratios or the like. In addition to the transverse balance, the structure is longitudinally balanced by the engine at one end and a rotary table at the opposite end of the frame 20 and these facts, with the lowered center of gravity produce a drive that is practically free of vibration.

The location of the engine at the far end of the frame from the rotary also provides 25 ample space at the intermediate portion of the frame for the hoist drum 39 and catchheads 40 which are driven by suitable gearing from the main drive shaft 14.

The convergently inclined cylinders are 30 shown as removably mounted on the lower portions of the two outermost uprights 32, 33 and the crank of the engine shaft operates between bearings carried by these two uprights. The driving sprockets 25, 26 are 35 mounted on an extension of the crank shaft between bearings carried by the intermediate and inner uprights 33, 34. In this way proper alignment and free operation is maintained and all parts are accessible and 40 open to inspection and repair. The engine bed may be bolted or otherwise suitably secured on the side beams in such a way that it may be readily removed from or mounted upon the frame.

45 What is claimed is:

1. A well drilling engine comprising in combination, a frame having side beams, a rotary table mounted at one end of the frame over said side beams, engine cylinders mounted at the opposite end of the frame over the side beams and inclined upwardly and inwardly on a convergent angle, a power shaft operated from said cylinders and mounted over the longitudinal center 50 line of the frame, a drive shaft arranged substantially on the longitudinal center line of the frame and extending from beneath said power shaft to the rotary table and sprocket gearing extending from the overhead power shaft down to the drive shaft beneath the same and controllable to operate 55 said drive shaft at different speeds relative to the engine shaft.

2. A well drilling engine comprising a 60 frame having side beams, a bed plate

mounted on said side beams at one end of the frame, a rotary table mounted on said bed plate, a bed plate mounted on the side beams at the opposite end of the frame, upright frames on said last bed plate, an engine shaft carried by said upright frames, convergently arranged engine cylinders carried by the upright frames and having power connections with the overhead engine shaft, a drive shaft including a section journaled on the engine bed plate below the engine shaft and a section coupled thereto and extending to the rotary table at the upper end of the frame and gearing from the overhead engine shaft down to said first mentioned drive shaft section.

3. A well drilling engine comprising a frame having side beams, a bed plate mounted on said side beams at one end of the frame, a rotary table mounted on said bed plate, a bed plate mounted on the side beams at the opposite end of the frame, upright frames on said last bed plate, an engine shaft carried by said upright frames, convergently arranged engine cylinders carried by the upright frames and having power connections with the overhead engine shaft, a drive shaft including a section journaled on the engine bed plate below the engine shaft and a section coupled thereto and extending to the rotary table at the upper end of the frame and gearing from the overhead engine shaft down to said first mentioned drive shaft section, said gearing including sprocket chains and gears on the engine shaft and drive shaft section controllable to operate the drive shaft at different speeds relative to the engine shaft.

4. A well drilling engine comprising an engine base having substantially triangular uprights, an engine shaft journaled at the head of said uprights, convergently inclined engine cylinders mounted at the base of said uprights and having power connections with the overhead shaft, a drive shaft mounted on the engine base beneath the engine shaft and back gearing from the overhead engine shaft down to said drive shaft.

5. A well drilling engine comprising an engine base having substantially triangular uprights, an engine shaft journaled at the head of said uprights, convergently inclined engine cylinders mounted at the base of said uprights and having power connections with the overhead shaft, a drive shaft mounted on the engine base beneath the engine shaft and back gearing from the overhead engine shaft down to said drive shaft, including sprocket pinions on said engine shaft, sprocket gears on said drive shaft, sprocket chains extending from the pinions on the engine shaft over the gears on the drive shaft and clutch means for selectively rendering the different sets of gearing operative to drive the drive shaft.

6. A well drilling engine comprising an engine bed, cylinders mounted at opposite sides of said bed and arranged on an upwardly convergent angle, a crank shaft mounted over the bed, power connections from the engine cylinders to said crank shaft, gears on said overhead crank shaft, a drive shaft mounted on the engine bed beneath the overhead drive shaft, gears on said 20 drive shaft coupled in driven relation to the gears on the overhead crank shaft, a frame having side beams spaced to receive and support opposite side portions of said engine bed, a rotary table journaled on said frame, 25 a shaft journaled on the frame for driving said rotary table and a coupling between said shaft and the drive shaft on the engine bed.
7. A well drilling engine comprising an engine bed, cylinders mounted at opposite sides of said bed and arranged on an upwardly convergent angle, a crank shaft mounted over the bed, power connections. 10
